JAMES A. BROGAN, OF LAWRENCE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR INSERTING FASTENINGS.

1,295,846.

Specification of Letters Patent.

Patented Mar. 4, 1919.

Application filed August 19, 1916. Serial No. 115,891.

To all whom it may concern:

Be it known that I, JAMES A. BROGAN, a citizen of the United States, residing at Lawrence, in the county of Essex and State 5 of Massachusetts, have invented certain Improvements in Machines for Inserting Fastenings, of which the following description, in connection with the accompanying drawings, is a specification, like reference characters 10 on the drawings indicating like parts in the several figures.

The present invention relates to machines for inserting fastenings into boots and shoes, and more particularly to the work gages 15 used in such machines for determining the distance of the line of operation of the fastening inserting mechanism from the edge of the work, the fastenings being successively inserted to form a row or rows par-

20 allel to the edge of the work.

In machines for inserting fastenings, the driving means usually performs its driving function in a predetermined path and the work into which the fastenings are driven 25 is moved relative thereto to properly position the fastenings. To guide the work in its movement such machines are usually provided with a gage against which the work is held and along which it is moved 30 after each fastening inserting operation. Where ornamental or wear resisting qualities are to be imparted to the heels of boots and shoes, fastenings are sometimes inserted in two or more rows parallel to the contour 35 edge of the heel in desired spaced relation. This is effected by a gage against which the exterior or contour surface of the heel is held and about which, as a center the shoe is swung. It is desirable, in some classes of

40 work, to continue the row or rows of fastenings across the heel parallel to the heel breast edge at a predetermined spaced distance therefrom, but owing to the construction of such machines and the relation of 45 the gage thereto no gaging surface is provided which will determine the spacing of the fastenings from the breast edge of the heel. Moreover, in order to permit the shoe to be swung into the position required for 50 inserting the fastenings across the heel parallel to the heel breast edge, the edge gage must first be moved to inoperative position.

An important feature of the present invention, therefore, consists of heel contour

edge gaging means and heel breast edge 55 gaging means selectively operable at will to determine the relation of a row of fastenings with the contour and breast edges of the heel.

Another important feature of the invention consists in causing one of said gaging means to be moved out of gaging position so as not to interfere with the movement of the work, when the other gaging means is moved into gaging position. 60 65

A further important feature of the invention consists in shifting the gaging position of the two gaging means so that the spaced relation of the parallel rows of fastenings about the heel contour and breast 70 edges may be varied at will and without special attention on the part of the operative.

Although the invention will be herein 75 after described in its application to the insertion of a row or rows of fastenings along both the contour edge and breast edge of a heel, it is recognized that it may be usefully employed in other relations. Consequently, nothing contained herein is intended to limit 80 the scope of the invention except as required by the claims.

Other features of the invention, as well as those noted, will hereinafter be fully described and definitely set forth in the claims. 85

In the drawings:—

Figure 1 is a side view of the upper or head portion of a slugger of known type having the present invention applied thereto.

Fig. 2 is an enlarged perspective view 90 showing the work gage detached and in position for the insertion of an outer row of fastenings.

Fig. 3 is a plan view showing the gage in three different positions. 95

Fig. 4 is an enlarged perspective view looking upward at the side of a modified form of the invention, parts being broken away.

Fig. 5 is a similar view of a portion of the 100 gage shown by Fig. 4 with the parts in a different position.

Fig. 6 is a diagrammatic view showing by full lines the relation of parts while inserting fastenings about the contour edge and 105 by dotted lines the relation of parts while inserting fastenings along the heel breast edge.

For the purposes of this description, the gage of the present invention may be considered as employed in connection with a machine for inserting ornamental or wear resisting slugs, such for instance as disclosed by the patent to Casgrain, No. 1,017,381, Feb. 13, 1912, but while the invention is particularly adapted for use in such machines, it may be employed advantageously in any 5 machine for inserting fastenings into boots and shoes and in other types of machines with which gages are desirably employed to determine a line of operation bearing a definite relation to the work. The term 10 "fastening" will hereinafter be employed in its general sense to include not only ornamental or wear resisting slugs, but all the usual forms of nails, tacks, and the like adapted to be inserted into leather. Moreover, 15 although the gage is described as being more particularly designed for gaging the breast and contour edges of heels, it is recognized that the invention in certain of its aspects is not restricted thereto. The invention 20 is therefore to be limited only by the scope of the appended claims.

Referring to the drawings, the fastening inserting mechanism is supported on the head frame 1 and comprises the driver-bar 30 2, which may carry one or more drivers 3 for inserting the fastenings into the work as fully disclosed by the patent mentioned, or the head frame and inserting mechanism may be embodied in other well known forms, 35 such for instance as disclosed by United States Letters Patent No. 786,190, granted March 28, 1905.

Pivottally connected to the head frame at 4 is an arm 5 provided with a hub portion 6 in 40 which is mounted a shaft carrying a crank pin 7. The crank pin 7 engages the slot 8 of an arm 9 having the upturned portion 10 guided by the groove 11 in the flattened portion 12, of the arm 5. The shaft carrying 45 the crank pin 7 has secured thereto a handle 111, Fig. 2, the construction being such that by movement of the handle 111, the arm 9 may be moved relatively to the supporting arm 5, all as more fully described in the patent 50 to Casgrain, No. 1,040,273, dated October 8, 1912. As pointed out in this patent, it is frequently desirable to insert into a heel two rows of fastenings spaced apart and parallel to the contour edge of the heel, and as a 55 means for limiting the spaced relation of the rows of fastenings the patent provides a stop plate, such as 13, Fig. 1, and a coöperating stop pin, which, with the parts above described, constitute means for adjusting the 60 gaging members through predetermined limits of adjustment.

The illustrated application of the invention 65 contemplates that fastenings be inserted in one or more rows parallel to the contour edge of the heel and also in one or more rows

across the heel parallel to the breast edge, and to this end provides gaging means, hereinafter sometimes referred to as heel contour edge gaging means, against which the exterior contour surface of the heel may be 70 held and with respect to which it may be moved while inserting the row or rows of fastenings parallel to the contour edge, and other gaging means, hereinafter sometimes referred to as breast edge gaging means, 75 against which the breast of the heel may be held and with respect to which it may be moved while inserting the row or rows of fastenings parallel to the heel breast edge, the two gaging means being so arranged 80 that when one is operatively positioned with respect to the inserting mechanism the other is inoperatively positioned and consequently out of the way.

Referring to the drawings, the supporting arm 9, Figs. 1 and 2, carries the contour edge gaging and breast edge gaging means, so that when either of said gaging means is in gaging position, movement of the supporting arm 9 by means of the handle 111, will serve to change the distance from the edge of the row of fastenings being inserted, and if a row of fastenings be inserted with the supporting arm 9 in one position and then its position be changed, another row of 95 fastenings parallel to the first row may be inserted.

In the form of the invention illustrated by Figs. 1, 2 and 3, the contour edge gaging means and the breast edge gaging means are 100 mounted upon a carrying member sustained by the supporting arm 9, so that when one of said gaging means is moved to gaging position the other is moved out of the way. In the present instance, Figs. 1, 2 and 3, a substantially T-shaped carrying member 15 is 105 pivotally mounted at 14 to the supporting arm 9 and has its free end portion provided with a bearing surface 16 adapted for use as a contour edge gaging means against which the exterior contour of the heel of a boot or shoe may rest to guide the heel as the shoe is swung to different positions for the insertion of fastenings parallel to the contour edge. The carrying member 15 has another 110 bearing surface at the opposite side thereof adapted for use as a breast edge gaging means against which the heel breast may rest to guide the heel as the shoe is moved to different positions for the insertion of fastenings parallel to the breast edge.

When the carrying member 15 is swung on the support 9 to place the contour edge gaging surface 16 in gaging position with respect to the driver 3, Fig. 3, the breast edge gaging surface 17 is moved from gaging position and does not interfere with the movement of the work in placing a row of fastenings in the heel parallel to the contour edge thereof. Similarly when the breast 130

edge gaging surface 17 is placed in gaging position with respect to the driver the contour edge gaging means is moved into an inoperative or non-gaging position and does 5 not interfere with the free movement of the work for placing a row of fastenings parallel to the breast edge of the heel.

In Fig. 2 and by full lines in Fig. 3, the 10 position of the swinging carrier 15 is shown such that the contour edge gaging surface 16 is in gaging relation with the inserting mechanism and by moving the heel α over the surface 16 a row of fastenings may be inserted in the heel parallel to the contour edge 15 thereof. When a row of fastenings is to be 20 inserted across the heel parallel to the breast edge, the carrier 15 is moved from the full line position, Fig. 3, to the lower dotted line position, to bring the gaging surface 17 into operative relation with the inserting mechanism and simultaneously with such movement the gaging surface 16 is moved forward, in this instance of the invention, so 30 that the breast of the heel may be placed against the gaging surface 17, substantially 25 as indicated by the dotted lines α' , Fig. 3. It will be apparent that when inserting fastenings parallel to the contour edge, the exterior surface of the heel will, in this instance of the invention, be pressed backwardly against the gaging surface 16, and when inserting 35 fastenings parallel to the heel breast edge, the heel breast will be pulled forwardly against the gaging surface 17. It becomes 40 desirable therefore, to provide stops to hold the carrier 15 in either position. In the present instance, the carrier 15 is extended beyond the pivotal connection 14 with the arm 9 and is provided with a handle 18 by which 45 the carrier may be moved to place one of the gaging surfaces in and the other out of gaging 50 position.

The arm 9 is provided with a projecting portion 19 in which is formed a suitable recess or opening 20 to be engaged by a stop pin 21 attached to a hand-piece pivoted at 22 on the handle 18. The stop pin 21 is guided in lugs 23 projecting from the handle 18, and a spring 24 normally acts to force the pin 55 21 into locking engagement with the opening 20 to hold the carrier 15 with the heel contour edge gaging surface 16 in gaging position and the heel breast edge gaging surface 17 out of gaging position.

55 By tripping the pin 21 from the opening 20 the carrier 15 may be moved to throw the gaging surface 17 forwardly into gaging position and the gaging surface 16 out of gaging position. A shoulder 25 on the carrier 15 is adapted to engage a stop lug 26 secured to the arm 9 when the breast edge gage 17 is in operative position. In the present instance the stop lug 26 is formed as a finger projecting from a part 27 secured 60 to the arm 9.

The distance of the row of fastenings from the contour and breast edges of the heel may be varied by means of the handle 111, through manipulation of which the arm 9 and perforce the gages 16 and 17 may be 70 moved to alter the relation of the gages and driver 3. By moving the handle 111 in appropriate directions two rows of fasteners may be inserted parallel to the contour and breast edges of the heel. 75

After a row of fastenings has been inserted, and located parallel to the contour and breast edges of the heel by the alternate movement of the contour edge and breast edge gaging means into gaging position, a 80 substantially continuous line of fastenings will extend about the contour and along the breast edges and in some cases this may be sufficient. In other cases, however, it is desirable to place two rows of fastenings in 85 spaced relation parallel to the contour edge of the heel and a single row across the heel parallel to the heel breast edge. To effect this the carrier 15, in the present instance of the invention, is permitted to have a further 90 backward movement than that defined by the opening 20 and pin 21, and a suitable stop is provided to locate the full back position of the carrier and consequently the distance of the second row of fastenings from the first 95 row.

The carrier 15 at the side of its pivotal connection with the arm 9 opposite the gages 16 and 17, is provided with a shoulder 28 adapted, when the carrier 15 is moved to its 100 full back position, to contact with a finger 29 secured to the supporting arm 9. In the present instance of the invention the finger 29 projects from a part 30, Fig. 2, secured to the arm 9 in a manner similar to the part 27. 105 The relation of the fingers 26 and 29 may be changed to permit different degrees of movement of the carrier 15, and a pin 31 may secure them in determined adjusted relation. 110

In Fig. 3 the position of the carrier 15 and the gaging means 16 for the insertion of a second row of fastenings parallel to the heel contour edge is represented by the upper dotted lines, the heel being indicated at α^2 115 with its exterior contour surface bearing against the gage 16.

In Figs. 4, 5 and 6 a modified form of the invention is shown, wherein the heel contour edge gaging means and the heel breast edge gaging means are formed independently and are moved, the one into and the other out of gaging position, in a somewhat different manner from that already described. The foot-plate or member 32, Figs. 4 and 5 120 has secured thereto, as by the screws 33, a bearing plate 34 against which the work is held. The bearing plate 34 is suitably recessed at each side of the opening 35, as at 36, Figs. 4 and 5, to receive the contour edge 125 130

gage 37 and the breast edge gage 38. The gage 37 is secured to the arm 39 which corresponds to the arm 9 of the preferred form of the invention already described, except that the arm 39 is formed as a spring normally acting to maintain the contour edge gage 37 seated in the recess 36 with its lower surface in the plane of the bearing plate 34. The breast edge gage 38 is mounted upon the 10 spring arm 40 secured at one end to the foot-plate or member 32, the construction being such that the spring arms 39 and 40 normally act to maintain the gages 37 and 38 within their respective recesses 36. A slide 15 41 is mounted in a guideway 42 formed in the bearing plate 34 and is provided with a cam piece 43 to act upon and project one or the other of the gages 37 and 38, according to the position of the cam piece. A finger piece 44 is connected to the slide 41, whereby it may be appropriately moved in the guideway 42, the construction and relation of parts being such that when the slide 20 41 is moved in one direction, it will project the contour edge gage 37 from its recess into gaging position and permit the breast edge gage to remain within its recess 36 out of the way. With the parts in this position, the exterior contour of the heel *b* Fig. 6, may be 25 held against the gage 37 and the heel be moved relatively to the driver to insert a row of fastenings parallel to the contour edge of the heel. Should a second row of fastenings be desired parallel to the contour 30 edge of the heel, the handle 111 may be moved to draw the contour edge gage 37 backward or to the left, Fig. 4. This position of the gage 37 is represented by the lower dotted lines, Fig. 6.

35 40 When a row of fastenings is to be inserted parallel to the breast edge of the heel, the slide 41 is moved to the position indicated by Fig. 5, whereupon the breast edge gage 38 is projected or moved into operative position by the cam 43, and the contour edge gage 37 is at the same time permitted to move to inoperative position within the recess 36 of the bearing plate. The breast of the heel may then be placed against the 45 breast edge gage 38, as represented by dotted lines in Fig. 6, and moved along the gage as the fastenings are successively inserted into the heel parallel to the breast edge by the inserting mechanism.

50 55 Claims:

1. In a machine of the character described, the combination of heel contour edge gaging means for determining the relation of a row of fastenings with respect to the contour edge of a heel, heel breast edge gaging means for determining the relation of a row of fastenings with respect to the breast edge of a heel, and means operable at will for selectively placing either of said gaging 55 means in gaging position.

2. In a machine of the character described, the combination of heel contour edge gaging means for determining the relation of a row of fastenings with respect to the contour edge of the heel, means for shifting the contour edge gaging means to another position for determining the relation of a second row of fastenings parallel to the contour edge of the heel, heel breast edge gaging means for determining the relation of a row of fastenings across the heel parallel to the breast edge of the heel, and means for selectively rendering either of said gaging means operative and the other inoperative. 70

3. In a machine of the character described, the combination of heel contour edge gaging means along which the contour portion of the heel is movable to determine the position of a row of fastenings with relation to the contour edge of the heel, heel breast edge 85 gaging means along which the breast of the heel is movable to determine the position of a row of fastenings with relation to the breast edge of the heel, means operable at will for placing one of said gaging means in 90 and the other out of gaging position, and means for shifting the gaging position of the contour edge gaging means to enable a plurality of rows of fastenings to be inserted parallel to the contour edge of a heel. 95

4. In a machine of the character described, the combination of heel contour edge gaging means, and heel breast edge gaging means for determining the relation of a row of fastenings with respect to the contour edge 100 and breast edge of a heel, means for moving one of said gaging means in and the other out of gaging position, means for shifting the gaging position of the contour edge gaging means for the insertion of a second row of fastenings parallel to the contour edge of the heel, and stops for determining the spaced relation of the two parallel rows of fastenings. 105

5. In a machine of the character described, the combination of gaging means for determining the relation of a row of fastenings with respect to the contour edge of a heel, means for moving the gaging means into a plurality of positions for the insertion of a 110 plurality of rows of fastenings parallel to the contour edge of a heel, heel breast edge gaging means along which the breast of a heel is movable for determining the relation of a row of fastenings with respect to the breast edge of a heel, and means constructed and arranged to effect movement of one of said gaging means into and the other out of gaging position. 115

6. In a machine of the character described, the combination of a gage along which the exterior contour of a heel is movable to position the heel for the insertion of a row of fastenings parallel to the contour edge of the heel, means for shifting the position of 120

the gage to enable additional rows of fastenings to be inserted parallel to the contour edge of the heel, a heel breast gage along which the breast of a heel is movable to enable a row of fastenings to be inserted across the heel parallel to the breast edge, and manually controlled means constructed and arranged to move one of said gages into gaging position and the other out of gaging position by a single operation of said means.

7. In a machine of the character described, the combination of an arm, heel contour edge gaging means and heel breast edge gaging means carried by said arm, and along which the heel contour and heel breast are respectively movable to permit a row of fastenings to be inserted in the heel parallel to the contour and breast edges and means for shifting the arm with either of said gages in gaging position to permit a plurality of rows of fastenings to be inserted parallel to either the contour or breast edge of the heel.

8. In a machine of the character described, the combination of an arm, heel contour edge gaging means and heel breast edge gaging means carried by said arm, and along which the heel contour and heel breast are respectively movable to permit a row of fastenings to be inserted in the heel parallel to the contour and breast edges, means for selectively placing either of said gages in gaging position, and means for shifting the arm with either of said gages in gaging position to permit a plurality of rows of fastenings to be inserted parallel to either the contour or breast edge of the heel.

9. In a machine of the character described, the combination of two gages, over one of which the contour portion of a heel is movable for determining the relation of a row of fastenings with respect to the contour edge of the heel and over the other of which the heel breast is movable for determining the relation of a row of fastenings with respect to the breast edge of the heel, stops for determining the gaging position of both of said gages, and means acting to simultaneously move one gage into gaging position and the other out of gaging position that the work may be freely moved with either gage in gaging position.

10. A gage for guiding the heel of a boot or shoe for the insertion of fastenings in rows parallel to the contour and breast edges, comprising, a contour edge gaging surface over which the contour of a heel may be moved during the insertion of fastenings in a row parallel to the contour edge of the heel, a stop for determining the distance of the row of fastenings from the contour edge of the heel, a second stop determining the distance of a second row of fastenings from the first row, a breast edge gaging surface over which the breast of a heel may be moved during the

insertion of a row of fastenings across the heel parallel to the breast edge, and a device co-operatively related with both of said gages to cause one to be maintained in inoperative position out of the way of the work when the other is in gaging position.

11. A gage for guiding the heel of a boot or shoe for the insertion of fastenings in a row parallel to the contour and breast edges, comprising, in combination, a carrier, a contour edge gage and a breast edge gage connected to said carrier, a stop for limiting movement of the carrier with the contour edge gage in position to permit a row of fastenings to be inserted parallel to the contour edge of the heel and with the breast edge gage out of gaging position, a second stop for limiting movement of the carrier and gages to a position for the insertion of a second row of fastenings parallel to the contour edge of the heel, and a third stop for limiting movement of the carrier to a position with the breast edge gage in gaging position and the contour edge gage out of gaging position.

12. A gage for guiding the heel of a boot or shoe for the insertion of fastenings in a row parallel to the contour and breast edges, comprising, in combination, a carrier, a contour edge gage and a breast edge gage connected to said carrier, a stop for limiting movement of the carrier with the contour edge gage in position to permit a row of fastenings to be inserted parallel to the contour edge of the heel and with the breast edge gage out of gaging position, a second stop for limiting movement of the carrier and gages to a position for the insertion of a second row of fastenings parallel to the contour edge of the heel, and a third stop for limiting movement of the carrier to a position with the breast edge gage in gaging position and the contour edge gage out of gaging position, a supporting arm on which the carrier is mounted, and means for adjusting said supporting arm to different positions that a plurality of rows of fastenings may be inserted parallel to the edges of the heel.

13. A gage for guiding a boot or shoe for the insertion of fastenings, comprising, in combination, a swinging carrier having oppositely extending portions constituting two gaging surfaces against either of which the work may be held to determine the position of the fastenings to be driven, means for pivotally supporting the carrier at a point offset laterally from the gaging portions for movement to place one of said gages in and the other out of gaging position, and stops for limiting the swinging movement of the carrier.

14. A gage for guiding a boot or shoe for the insertion of fastenings, comprising, in combination, a swinging carrier having oppositely extending portions provided with

two gaging surfaces against either of which the work may be held to determine the position of the fastenings to be driven, means for pivotally supporting the carrier at a point 5 relatively remote from said gaging surfaces and spaced laterally from a plane transverse to the planes of the gaging portions of the carrier and passing through the gaging surfaces for movement to place one of said 10 gages in and the other out of gaging position, and stops for limiting the swinging movement of the carrier.

15. In a gage of the character described, a support, a carrier mounted on said support 15 and having spaced gaging surfaces for alternative contact with edges of the work to be gaged to determine lines of operation parallel to said edges, means for mounting the carrier for movement of the gaging surfaces into and out of operative position, and means for defining a plurality of positions of adjustment of one of said gaging surfaces relative to said support to determine a plurality of lines of operation parallel 20 to one of said edges.

16. In a gage of the character described, a support, a carrier mounted on said support and having spaced gaging surfaces for alternative contact with edges of the work to 30 be gaged to determine lines of operation parallel to said edges, means for defining a plurality of positions of adjustment of the carrier relative to said support in one of which one of said gaging surfaces is rendered operative and another of said gaging surfaces inoperative and in another of which the other of said gaging surfaces is rendered operative and the first of said surfaces inoperative, and means for defining a third 35 position of adjustment of the carrier relative to the support to determine a second line of operation parallel to one of said edges.

17. In a gage of the character described, 45 gaging mechanism having a plurality of spaced gaging surfaces to engage edges of the work to be gaged, either of said gaging surfaces when in operative position determining a line of operation parallel to an edge of the work, means for defining a plurality of positions of adjustment of the 50 gaging mechanism to render said gaging surfaces relatively operative and inoperative, means for defining a third position of adjustment of one of said gaging surfaces to determine another line of operation parallel 55 to one of the edges of the work, and means for adjusting said gaging mechanism between predetermined limits of adjustment when either of said gaging surfaces is in 60 operative position to determine another line of operation parallel to either of said edges.

18. In a machine for operating on the heel 65 of a shoe, members having gaging surfaces spaced from each other, one of said gaging surfaces when in operative position being

in advance of the operative position of the other gaging surface, means for supporting said members constructed to render either of said gaging surfaces when in operative position accessible from below for presentation of a heel thereto after attachment to a shoe and constructed further to permit operation on the tread surface of the heel from above, and means for connecting the member having one of said gaging surfaces 70 to said supporting means for movement of said member relative to said supporting means in a direction substantially at right angles to the plane of its gaging surface 75 allowing operative engagement of the work 80 with the other gaging surface.

19. In a machine for operating on the heel of a shoe, members having gaging surfaces spaced from each other one of which when in operative position faces in a direction opposite to that in which the other gaging surface faces when in operative position, means for adjustably supporting said members constructed to render either of said gaging surfaces when in operative position 85 accessible for presentation of a shoe heel thereto from below for operation on the tread surface of the heel after attachment to a shoe, means for supporting the member having one of said gaging surfaces in position for engagement with the contour edge 90 of a heel to determine a line of operation about the contour edge of the heel of a shoe, and means for supporting the other of said members in a position for engagement with 95 the breast edge of the heel to determine a line of operation parallel to such edge of the heel.

20. In a machine for operating on a heel, an adjustable member formed with opposed 105 gaging surfaces, and means for defining a position of adjustment of said member in which one of said gaging surfaces is positioned for engagement with the contour edge 110 of the heel to determine a line of operation parallel with the contour edge of the heel, and means for defining another position of adjustment of said member in which the other of said gaging surfaces is positioned for engagement with the breast edge of the 115 heel to determine a line of operation parallel with the breast edge of the heel.

21. In a machine for operating on a heel, a carrier, a member having opposed gaging surfaces mounted on said carrier, means for 120 defining a position of adjustment of said carrier in which one of said gaging surfaces is positioned for engagement with the contour edge of the heel to determine a line of operation parallel with such edge of the heel, and means for defining another position of adjustment of said carrier so related 125 to the first-mentioned means and to the interval between said opposed gaging surfaces as to position the other gaging surface for 130

engagement with the breast edge of the heel to determine a line of operation parallel to such edge of the heel and spaced from such edge by a distance substantially equal to 5 that by which the first-mentioned line of operation is spaced from the contour edge of the heel.

22. In a gage of the character described, a carrier, a member having opposed gaging surfaces mounted on the carrier, a support for the carrier, said carrier being adjustable on its support to effect bodily movement of said member to position either of said gaging surfaces selectively in operative position, and means for effecting adjustment of 15 said support through predetermined limits when one of said gaging surfaces is in operative position.

23. In a gage of the character described, 20 a T-shaped member having gaging surfaces adjacent to the ends of the shorter arm of said member, and means for supporting said

member for bodily adjustment of said shorter arm to bring either of said gaging surfaces into operative position. 25

24. In a gage of the character described, a T-shaped member having opposed gaging surfaces at the ends of the shorter arm of said member, and means for pivotally supporting said member for bodily adjustment 30 of said shorter arm to bring either of said gaging surfaces into operative position.

25. In a gage of the character described, a T-shaped member having opposed gaging surfaces at the ends of the shorter arm of 35 said member, means for supporting said member for bodily adjustment of said shorter arm to bring either of said gaging surfaces into operative position and means for moving said member bodily through 40 predetermined limits of movement.

In testimony whereof I have signed my name to this specification.

JAMES A. BROGAN.
